UNITED STATES PATENT OFFICE.

CHARLES L. CASSIDY, OF ORANGE, NEW JERSEY.

SOCKET FOR ELECTRIC LAMPS.

1,140,498.

Specification of Letters Patent. Patented May 25, 1915.

Application filed February 28, 1914. Serial No. 821,815.

To all whom it may concern:

Be it known that I, CHARLES L. CASSIDY, a citizen of the United States, and a resident of Orange, county of Essex, and State of New Jersey, have invented certain new and useful Improvements in Sockets for Electric Lamps, of which the following is a specification.

My invention relates to sockets for use with incandescent electric lamps; and my object is first, to make the shell of the socket out of a single piece, and thus avoid the usual joint in the shell; second, to provide a socket in which the plug may be removed from the shell, and replaced therein, without the necessity of feeding or withdrawing the wire cable through the fixture tube; third, which shall in addition contain simple and effective means for retaining and locking the plug in position within the shell; and fourth, to improve the shade supporting means.

These and other objects will more fully appear from the following specification and accompanying drawings, considered together or separately.

In the drawings, Figure 1 is a cross-section of a socket embodying my invention; the dotted lines represent the plug removed from the shell. Fig. 2 is a top view of the plug. Fig. 3 is an elevation, partly in section, of the plug, taken at right angles to the plug shown in Fig. 1. Fig. 4 is a bottom view of the socket, with the plug in place; and Fig. 5 is a view in perspective of the plug retaining means.

In all of the views, like parts are designated by the same reference characters.

The shell 1 is made preferably of sheet metal, and is shown for the purposes of illustration as bell-like in shape. It is preferably made in a single piece, as shown. At its upper end it may be fastened in any suitable manner, to a neck 2, or this neck may be made integral with the shell. The neck 2 is shown with internal screw-threads, so that it may be attached to the ordinary fixture tube 3. The lower part of the shell 1 has a skirt 4. This skirt is preferably integrally formed on the shell.

Inside of the shell 1 is a plug 5. This plug is made of porcelain or any other suitable insulating material. It is of a size and shape adapted to fit within and only partly fill the shell, leaving a pocket 6 between it and the top of the shell. In this pocket lies

a coil 7 of the electric wire cable 8. By providing this coil of excess wire the plug may be removed from the shell for inspection or for connecting to the wire without disturbing the main cable by pulling it partly through the fixture tube and obviates the necessity of feeding it back in the tube, as has been the practice, when the plug is replaced in the shell. The lower part of the plug is illustrated as containing the ordinary type of fitting 9 employed with lamps having an Edison base. If a lamp having a different type of base is employed, the fitting will be correspondingly changed. The strands of the cable 8 are connected to the fitting 9 by binding posts 10. The connections and wires are placed in channels 11 of the plug and are made in the manner well known in the electric art.

The plug may, for the purpose of accessibility, be made in two sections, as shown, the two sections being held together by any suitable means, such as a screw 12. A hollow space 13 is left between the two sections, which may be occupied by an electric switch in that type of socket which employs a key and is known as a key-socket. The socket shown does not contain a switch, but is controlled by a switch at some other point in the circuit.

The plug is held in place in the shell in the following manner: In the skirt 4 are eyelets 14. These eyelets are riveted to the skirt and form projections 15 on the inside of the skirt 4. The eyelets are also provided with internal screw-threads to accommodate set screws 16 for holding a globe, or shade, in position. A flexible ring 17 is provided with holes 18, which register with the projections 15. The ring 17 is also provided with inwardly projecting ears 19. These ears are of a size and shape to correspond with and fit into notches 21 in the bottom face of the plug. The engagement of the ears 19 and the notches 21 serve to prevent the plug from rotating when the ring 17 is in place. The ears are also preferably offset, as shown, to engage with an annular groove 20 on the bottom of the plug. The annular groove 20 in the face of the plug is provided to accommodate the different sizes of flanges on lamp-shades, or globes, which are secured to the socket in the ordinary manner by the set screw 16.

The socket is assembled in the following manner: When the shell is secured to the

fixture, the cable 8 will extend outside of the shell. The strands of the cable will each be secured to its proper binding post 10 on the plug, and the latter will be placed within the shell with the notches 21 midway between the projections 15. The ring 17 is now introduced within the skirt in an inclined position so that two of the projections 15 will be in engagement with two of the openings 18. The side of the ring carrying the third opening is now flexed inward so that the opening passes over the projection adjacent thereto when the ring will be securely held in place. The engagement of the ears 19 with the bottom face of the plug will effectually prevent its removal and their engagement with the sides of the notches 21 will prevent rotation of the plug.

To dismantle the device the side of the ring at one of the projections is flexed inward until it is free from that projection, when it may be lifted from the socket formed by the skirt until the edge having the ears is beyond the edge of the skirt. The ring may be removed by sliding it diagonally from the socket. After the ring is removed, the socket may be pulled out to the full length of the surplus cable in the chamber when the socket can be removed by disengaging the wires from the binding posts.

Around the edge of the recess carrying the fitting 9 is a projecting annular rim 22 which acts as an insulating barrier between the metal fitting 9 and the ears 19 of the ring 17.

The arms 19 are preferably flexible to allow for variations in the size and shape of plugs. It is understood that the annular groove 20 when omitted from the plug will permit the use of arms which are not off-set, as previously described. It is also to be understood that the improved means for retaining and locking the plug in position may be embodied in a socket which does not possess the pocket 6, and vice versa, the invention may be embodied in a socket which possesses the pocket, but without the improved means for retaining and locking the plug in position.

From the foregoing description it is apparent that the socket has a cup shaped shell in the open end of which the plug is inserted and secured in place, the shell being

in one piece and entirely inclosing the plug. The joint necessary in a two-piece shell is avoided. The support for the globe is integral with the shell, thus avoiding a separate fastening.

I claim:

1. In a socket for an electric lamp, the combination with an electric cable, of a metallic shell closed at one end and open at the other end, an insulating plug introducible into the open end of the shell to close the opening, and having connecting means for the cable, said plug extending only part way to the closed end of the shell, leaving a space for a coil of the cable of sufficient length to permit the withdrawal of the plug to render the connecting means accessible and means for removably securing the plug to the shell, and means for preventing rotation of the plug.

2. In an electric lamp socket, the combination with an electric cable, of a shell, a plug partly filling the shell and leaving a space between it and the shell for a coil of the electric cable, a ring engaging with the plug and holding it in place, means for securing the ring within the shell and means on the ring to prevent the plug from rotating.

3. In an electric lamp socket, the combination with a shell with eyelets adjacent to the free end thereof, of a plug within the shell, said plug having notches in its exposed face, a ring having openings adapted to engage with the eyelets, and having ears adapted to engage the notches of the face of the plug.

4. In an electric lamp socket, the combination with a shell with eyelets adjacent to the free end thereof, of a plug within the shell, said plug having notches in its exposed face, an annular groove adjacent to its periphery, a ring having openings adapted to engage with the eyelets, and ears adapted to engage with the notches on the face of the plug, said ears being offset to engage with the annular groove.

This specification signed and witnessed this 21st day of February, 1914.

CHARLES L. CASSIDY.
